UNITED STATES PATENT OFFICE.

MAX SCHULTZ, OF BUFFALO, NEW YORK.

FOOT-PROTECTOR.

No. 893,876.

Specification of Letters Patent. Patented July 21, 1908.

Application filed March 23, 1908. Serial No. 422,645.

To all whom it may concern:

Be it known that I, MAX SCHULTZ, a citizen of the United States, residing at Buffalo, in the county of Erie and State of New York, have invented a new and useful Improvement in Foot-Protectors, of which the following is a specification.

This invention relates to the foot protectors which are worn within a shoe for relieving corns, bunions and swollen or dislocated joints from pressure and irritation. A protector of this kind is shown and described in Letters Patent of the United States No. 840,717, granted to me January 8, 1907. The protector of this patent comprises a tip adapted to fit over the front portion of the foot and a shield secured to the tip and provided with pads arranged to rest against the foot on the front and rear sides of the bunion. One of the objects of my present invention is to provide the shield with an adjustable pad which can be readily reduced in thickness to accommodate it to the particular foot on which the protector is to be worn, thus adapting the same protector to corns, bunions or swellings of different sizes and avoiding the necessity of manufacturing and carrying in stock a large variety of such protectors with different-sized pads.

A further object of the invention is to provide a protector of this kind which will shield the top of the foot, so as to relieve corns and top bunions from pressure and irritation.

In the accompanying drawings: Figure 1 is a perspective view of a gaiter containing the improved protector, the gaiter being partly broken away to expose the protector. Fig. 2 is a horizontal section of the protector, taken centrally through the pads. Fig. 3 is a perspective view of the protector showing the shield at the top of its tip. Fig. 4 is a vertical longitudinal section of the last-named protector. Fig. 5 is a longitudinal section of the laminated pad, showing a modification thereof.

Similar letters of reference indicate corresponding parts throughout the several views.

Referring to Figs. 1 and 2, A indicates the tip of the protector which fits over a number of the toes of the foot and which is preferably provided with ventilating openings a. B indicates the shield secured at its front end to one side of the tip and curved to conform to the side of the foot to be protected, as shown in the drawings and in the Letters Patent hereinbefore referred to. In the construc-

tion shown in Figs. 1 and 2, the shield is applied to the inner side of the foot to protect a side bunion or swollen toe joint. C is the opening or recess which receives the bunion and D, D¹ the pads or cushions applied to the inner side of the shield immediately in front and in rear of said opening for relieving the bunion from the pressure of the shoe. As shown in Fig. 2, the rear pad D¹ preferably is comparatively thin and composed of a single layer or thickness of wool, felt or other suitable cushioning material. The front pad D is of similar material and consists of a plurality of layers d, say three, which can be readily separated, so that one or more of the inner layers can be readily detached from the remaining layer or layers for reducing or adjusting the thickness of the pad to suit the particular foot to be relieved. For this purpose, the several layers of the pad are united for a part of their length or at one end or edge, preferably the end nearest the opening C, while their opposite or front portions are disconnected so that the free end of one or more of the layers can be conveniently seized and stripped from the remaining layers for thinning the pad as required. In the preferred construction of the pad, its layers are glued together, but they may be fastened together by stitching or otherwise, if desired. As shown in the drawings, the pads are preferably thinned toward the opening C.

When the invention is embodied in a side shield, as shown in Figs. 1 and 2, only the front pad D need be made of layers, because a thin pad of a single thickness or layer is usually sufficient for the rear pad D¹. In the construction shown in Figs. 3 and 4 the shield B¹ is secured to the top of the tip A¹ for protecting a top bunion or a corn. When the improved pads D² are applied to such a top-shield, they are both preferably laminated, as shown in Fig. 4.

Instead of making the pad of separate layers glued or otherwise secured together at one end or edge, it may be constructed of a solid piece of cushioning material slit for a part of its length to form readily-detachable layers d¹, as shown in Fig. 5.

It will be understood from the foregoing that the improved protectors are supplied to shoe-dealers with adjustable pads of maximum thickness, and if a dealer wishes to fit a protector to a foot requiring a thinner pad, he simply tears off one or more layers of the pad to reduce it to the required thickness.

This adjustable construction of the pads simplifies the manufacture of the protector and does away with the necessity on the part of dealers of carrying a large number of protectors with different sized-pads.

While the adjustable pads are herein shown in connection with a shield having a toe-tip, they may be applied to shields having no such tips, if desired.

10 I claim as my invention:

1. A foot protector, comprising a shield and a pad applied to the shield and consisting of a plurality of layers united for a part of their length and disconnected for the remainder of their length, substantially as set forth.

2. A foot protector, comprising a shield having an opening, and a pad applied to the shield adjacent to said opening and consisting of a plurality of layers, said layers being

united at the ends nearest the opening and disconnected at their opposite ends, substantially as set forth.

3. A foot protector, comprising a shield having an opening, and a pad applied to the shield adjacent to said opening and constructed of increasing thickness from the opening toward the opposite end of the pad, the pad consisting of layers which are disconnected at the thick end of the pad and united at the opposite end thereof, substantially as set forth.

Witness my hand this 19th day of March, 1908.

MAX ^{his} SCHULTZ.
